UNITED STATES PATENT OFFICE.

EDWARD B. BIRKENBEUEL, OF PORTLAND, OREGON, ASSIGNOR TO COIN MACHINE MANUFACTURING COMPANY, OF PORTLAND, OREGON, A CORPORATION OF OREGON.

COIN-DELIVERING MACHINE.

1,139,838.

Specification of Letters Patent. Patented May 18, 1915.

Application filed August 8, 1912. Serial No. 714,084.

To all whom it may concern:

Be it known that I, EDWARD B. BIRKENBEUEL, a citizen of the United States, residing at Portland, in the county of Multnomah and State of Oregon, have invented certain new and useful Improvements in Coin-Delivering Machines; and I do hereby declare the following to be a full, clear, and exact description of the same, reference being had 5 to the accompanying drawings, forming part of this specification, and to the figures and letters of reference marked thereon.

This invention relates to coin delivering apparatus and has for its object the provision of an exceedingly simple and effective mechanism, wherewith by the operation of any one of a plurality of keys a selecting mechanism may be first set and then operated for ejecting coins of the denomination which it is desired to deliver, the coins delivered being of a predetermined character and value to equal the amount indicated by the key.

Referring to the accompanying drawings,—Figure 1 is a perspective view of the essential parts of the operating mechanism of a machine embodying the present improvements, certain of the parts being broken away and omitted, in order to 15 simplify the illustration; Fig. 2 is a vertical section through a coin delivering machine, embodying the present improvements, this view being designed more particularly to illustrate the relative arrangement of the 20 coin holders, ejectors and their selecting and operating mechanism. Fig. 3 is a fragmentary horizontal section taken through the coin holders and looking downwardly.

Like letters of reference in the drawings 25 indicate the same parts.

In the simple form of machine illustrated, four vertically movable keys A are mounted on stems A' guided for vertical movement in frame plates B. Each of said keys is provided on one side with an incline a, adapted to coöperate with a sliding plate or member D, through which the key stems are adapted to pass. The apertures d in plate D, through which the stems of the keys pass 30 and with one wall of which the inclines A coöperate to move the slide or plate D longitudinally, are of different size and the normal position of the plate is such that the downward movement of the several keys will impart different degrees of movement to 55 the plate. Obviously, the same result may be accomplished by making the inclines of graduated height or inclination, but each stem should be provided with a parallel edge surface a', which will serve as a stop to hold 60 the plate D in its advanced position, during the continued or final portion of its movement.

The plate D referred to, constitutes the initial operating mechanism for positioning the selector, and while it may be directly connected therewith it is preferably connected through a lever mechanism, whereby the motion may be somewhat increased and a lateral and transverse freedom 70 of movement permitted the selector for the purpose of operating the ejectors, all as will be presently explained.

Below the keys A there is journaled a shaft E constituting the support for an incline F with which the lower ends of the key stems are adapted to coöperate for imparting an angular movement to the shaft. The incline F may conveniently be carried by arms f keyed to the shaft and the lower ends 80 of the key stems are provided with antifriction rollers G for coöoperating with the incline, said rollers adapted to engage the incline and rock the shaft after the keys have descended to a point where the plate or 85 ejector operating member D has practically completed its longitudinal movement. The shaft E also carries a frame H constituting the selector support and ejector operating means, to which end it is provided with a 90 guideway h for a longitudinally movable selector I. The selector I will partake of the angular movements of the shaft E and it is positioned longitudinally through its connections with the plate D. In the simple form of connections illustrated, a lever K is pivotally mounted at k on the frame of the machine and at an intermediate point is connected through pin and slot connections k' with the plate D. At its upper end 95 it is provided with a pin L working in a vertical slot or between abutments l on the

ejector. With this arrangement, movement of the plate D will position the selector I longitudinally and at the same time said selector is free to move laterally or angularly with the shaft E, while being held in its longitudinal adjustment, through its co-operation with the pin L.

The selector I is provided with projections *i* properly positioned thereon to coöperate with downward extensions *m* of ejectors M, the longitudinal adjustment or position of the selector determining which of the projections *i* shall be in position to coöperate with the ejectors, and it is obvious that by properly positioning the projections *i* the keys may be made to operate any desired combination of the ejectors or any single ejector for delivering coins or a coin of the desired value.

20 The ejectors are returned to normal position by a bar H' lying in front of the projections *m* and itself preferably constituting a part of the frame H in which the selector slides.

25 The particular manner of mounting the ejectors and of arranging the coin holders is not material to the present invention, but as illustrated in Fig. 2, it will be seen that the coin holders N are provided at the bottom 30 with slots *n* through which the ejectors M are adapted to pass to eject a coin or coins from the bottom of the stack in the holder, said coins passing down through a suitable delivery opening into a tray or receptacle O.

35 The ejectors illustrated, are provided with longitudinal slots M' and through the slots a guiding and supporting bar P is passed for retaining and supporting the ejectors in proper operative position with relation to 40 the coin holders.

The angular movement of the shaft E and of the ejector selecting and operating mechanism is slight, being only sufficient to advance the coins beyond the supporting ledges 45 in the holders and hence the incline F with which the key stems coöperate may be made relatively steep, thereby materially reducing the pressure necessary for ejecting the coins and correspondingly lightening the key action 50 of the machine.

The parts may be all returned to normal position by light springs, thus the keys are elevated by springs such as that indicated 55 by Q in Fig. 1, and the selector plate by a spring such as that indicated at R.

Having thus described my invention, what I claim as new and desire to secure by Letters Patent of the United States, is:

60 1. In a key operated coin delivering machine, the combination with a plurality of coin holders and a separate ejector for discharging coins from each coin holder, of a longitudinally and laterally movable selector adapted to coöperate with each of said

ejectors, a plurality of keys and operating connections intermediate the keys and selector for imparting, first, a differential longitudinal movement to position the selector and then a lateral movement to operate the selected ejectors.

2. In a key operated coin delivering machine, the combination with coin holders and ejectors for discharging coins therefrom, of a longitudinally movable selector adapted to coöperate with the ejectors, an angularly movable frame in which said selector is movable longitudinally, a plurality of keys, and differential operating connections intermediate the keys and selector for differentially positioning the same longitudinally, and operating connections intermediate the keys and angularly movable frame for imparting angular movement to the selector for operating the ejectors.

3. In a key operating coin delivering machine, the combination with coin holders and ejectors for discharging the coins therefrom, of a longitudinally movable selector having projections thereon for coöoperating with the ejectors to operate the same, a laterally movable frame in which said selector is mounted having a projection thereon for coöoperating with the ejectors to return them to normal position, and a plurality of keys for controlling the longitudinal movement of the selector and the lateral movement of the frame and selector.

4. In a key operated coin delivering machine, the combination with coin holders and ejectors for discharging coins therefrom, of a series of keys, inclines on said keys, an ejector operating selector with connections operated by said inclines for positioning the selector longitudinally, a rock shaft, a frame carried by said rock shaft, and in which the selector is mounted, and an incline with which the keys coöperate to impart angular movement to the shaft and selector.

5. In a key operated coin delivering machine, the combination with coin holders, ejectors for discharging coins therefrom, and a series of keys, of a selector for coöperating with the ejectors, an angularly movable frame in which said selector is mounted, a selector operating plate, inclines on the keys for moving said plate to position the selector longitudinally, and an incline connected with the selector carrying frame and with which the keys coöperate for imparting angular movement to the selector for operating the ejector.

6. In a key operated coin delivering machine, the combination with coin holders, ejectors for discharging coins therefrom and a longitudinally and angularly movable selector for coöperating with said ejectors, of operating mechanism for said selector embodying finger keys, inclines moved by said

keys, a selector operating member with which said inclines coöperate, a loose connection between said member and selector, whereby the selector is permitted a lateral 5 movement, a rock shaft on which the selector is mounted for lateral movement, and a single incline carried by the rock shaft in

alinement with the keys and adapted to be displaced laterally by the operation of said keys.

EDWARD B. BIRKENBEUEL.
